ALBERT LETREUX, OF CONSTANTINE, ALGERIA

APPARATUS FOR AUTOMATICALLY COUNTING THE VOLUMES OF GRANULOUS MATERIALS PASSING THROUGH THE SAME

Application filed July 18, 1927. Serial No. 206,769.

This invention relates to an apparatus for automatically counting the volumes of granulous materials essentially calibrated and not agglomerated, which traverse said apparatus and of whatever density the materials may be, and for indicating the number of volume-units by a counter.

This apparatus is designed to be used for controlling the quantities of grain charged into mills, thrashing-machines, silos or the like. The apparatus might further be used for calculating the specific weight of a crop by measuring the same prior or after the weighing.

15 An embodiment of the invention is illustrated, by way of example, in the accompanying drawing, in which:—

Fig. 1 shows the apparatus in front elevation the drum being partly in section.

20 Fig. 2 is a section on line A—A of Fig. 1.

Fig. 3 shows, viewed in the same direction as Fig. 2, the cam and the driving mechanism for the counter.

The apparatus comprises a charging hopper 1 into which the material to be measured is poured, and which has two doors, the one door 2 having to be opened by hand when the apparatus is started, the other door 3 being closed automatically each time the apparatus functions, but opening automatically at every stop, as will be hereinafter explained.

25 The grain drops from the charging hopper 1 into a distributing hopper 4 of smaller size, the walls of which are inclined at an angle which permits of the rolling down of any grain which is usually handled.

30 This distributing hopper 4 is supported by two frames 5, loosely mounted on the journals 6 of a measuring drum 7, so that this distributing hopper is rigid with the journals 6 and with the drum 7 and participates in the ascending and descending movements of said drum, the distributing hopper being hingedly connected to connecting rods 8, 8 which are connected themselves to the machine-frame 9.

35 The measuring device proper may consist of any system fulfilling the working conditions of the apparatus. In the form of construction shown, this measuring device con-

sists of a cylindrical-drum 7, adapted to rotate around a horizontal axis 6, 6 and which consists of two arms united by partitions 10 which subdivide said drum into four buckets which are partly closed towards the outer side, i. e. at the periphery of the drum, by doors 11^a, 11^b, 11^c, 11^d movable around hinges 12. That part of the circumference which is open serves for filling the corresponding buckets. Partitions 20 in each bucket permit of the complete filling of the bucket when it is in the charging position and consequently of the measuring of a predetermined quantity of material and always of the same quantity.

40 The measuring drum 7 is suspended by its journals 6, 6 in a scale-beam 13 pivotable around axles 14, 14 and carrying at its other end an adjustable counter-weight 15. This counterweight 15 is adjustable by inserting a suitable quantity of shot or other weighty material in the cavity 15^a.

45 Four pulleys 16^a, 16^b, 16^c, 16^d are mounted each one on the outer side on one of the arms of the drum 7, and they are designed to stop the rotating movement of this drum, as will be hereinafter explained.

50 The elements of the system are arranged in such a manner that, in the position of rest, the distributing hopper 4 pours its contents into a bucket of the measuring drum, situated at one side of the vertical central axis, so that the weight of the material, which fills this bucket, has the tendency to make the drum rotate. This movement is however prevented by one of the pulleys 16^a, 16^b, 16^c, 16^d butting against the steep incline 17^a of a groove 17 of a stationary cam 19 carried by the machine-frame and as long as the drum 7 occupies its charging position.

55 The operation of the apparatus is as follows:

60 Normally the drum 7 being empty, this drum and the distributing hopper 4 are in the upper position shown in the drawing and owing to the action of the counter-weight 15. In this position the door 3 of the charging hopper 1 is lifted, as it is connected to the distributing hopper 4 by the links 18, 18. The material drops therefore into the dis-

tributing hopper 4 and thence into that bucket of the measuring drum which is standing underneath the distributing hopper. As soon as the grain drops into this bucket the weight 5 of the grain tends to make the drum 7 rotate in clockwise direction, this rotating movement being however prevented by the roller 16^a butting against the steep incline 17^a of groove 17 of the stationary cam 19. The 10 grain continuing to drop into the distributing hopper 4, the whole constituted by the drum and this distributing hopper, begins to equilibrate the counter-weight 15 and an oscillating movement around the axles 14 begins. The 15 Owing to this movement the roller 16^a gets onto the inclined part 17^b of groove 17 of the cam and the drum, being thus liberated, executes a quarter revolution until the next 20 following pulley 16^b, after having come into engagement with the groove 17 of cam 19, buts against the steep incline 17^a of the groove and starts thus the lifting of the scale-beam.

The door or flap 11^a has remained closed 25 during almost the entire duration of this part-rotation, as it is held by sectors 21, but at the end of this part-rotation the door 11^a getting away from the sectors 21, drops in outward direction until it strikes against cork-buffers 22 so that the emptying of the bucket begins. The oscillating system re-ascends then under the action of the counter-weight 20 15 and all elements return into the initial position, the drum having carried out a quarter revolution.

During the disengaging of the apparatus, which is composed of an oscillating movement and of a quarter revolution, the door 3 of the charging hopper has been closed as it 40 has been drawn along by the distributing hopper 4 so that no material can get lost.

During the rotation the contents of the bucket have been levelled by a metal-brush 23 arranged around the lower end of the distributing hopper 4, so that no grain can drop 45 out of the bucket during the filling of the same.

The doors of drum 7 close automatically at the rotation of the drum.

50 The distributing hopper which, at the oscillating, must contain a certain quantity of grain in order that the bucket may be always filled at this movement, permits of the oscillating movement being produced at a predetermined weight, so that, when the grains are thick, it will contain very little material while, when the grain is less thick, it will be almost full. Although the distributing hopper participates in the oscillating movements by its weight, the grain contained in the distributing hopper does not participate in the rotation nor subsequently in the measuring of the volume.

60 The pulleys 16^a, 16^b, 16^c, 16^d act, when running in the groove 17 of the stationary cam

19, successively upon a finger 24 which controls the counter 25 which registers thus the volumes of the material which has passed through the drum. This counter 25 is mounted on a lug 27^a of a support 27 on the other side of which the stationary cam 19 is fixed by means of screw-bolts, the heads of which are turned towards the counter so that, when this counter is secured by a lead-seal, it is impossible to touch its driving device, as the 75 same is covered by said cam.

I claim:—

An apparatus for automatically measuring grains comprising in combination, a drum subdivided into several buckets of predetermined volume and having inclined partitions in the corners for ensuring the complete filling, a hinged door for each bucket closing a portion of this bucket in leaving the other portion always open, sectors for maintaining said doors closed during a part rotation of the drum, a scale beam on one arm of which said drum is mounted, an adjustable counter weight arranged on the other arm of said scale beam for maintaining said drum in the raised position, a distributing hopper above the open portion of that bucket which is actually in the upper portion of the rotating drum, two frames supporting said distributing hopper and loosely mounted upon journals of said drum, hinged connecting rods supporting said frames in upright position so that they can ascend and descend with said drum, a charging hopper above said distributing hopper and designed to supply material to the latter, a fixed cam having a groove with a steeply inclined branch, rollers fixed on one side of the drum and designed to engage with said cam groove for stopping the drum for the filling of a bucket, a counter mechanism, and an arm operated by each of said rollers and designed to operate said counter mechanism.

In testimony whereof I affix my signature.
